H. MOORE'S APPARATUS for Condensing AIR
 assigned to Self & Aaron W. Knapp

Fig. 1

UNITED STATES PATENT OFFICE.

HALSEY MOORE, OF BANGALL, NEW YORK, ASSIGNOR TO HIMSELF AND
AARON W. KNAPP, OF SAME PLACE.

IMPROVEMENT IN AIR-CONDENSING APPARATUS.

Specification forming part of Letters Patent No. 75,042, dated March 3, 1868.

To all whom it may concern:

Be it known that I, HALSEY MOORE, of Bangall, in the county of Dutchess and State of New York, have invented a new and useful Improvement in Apparatus for Condensing Air; and I do hereby declare that the following is a full, clear, and exact description thereof, which will enable those skilled in the art to make and use the same, reference being had to the accompanying drawings, forming part of this specification, in which—

Figure 1 is a top or plan view of my improved apparatus. Fig. 2 is a vertical section of the same, taken through the line *x x*, Fig. 1.

Similar letters of reference indicate corresponding parts.

My invention has for its object to furnish an improved apparatus for condensing air for use in driving an air-engine; and it consists in the construction, combination, and arrangement of the various parts of the apparatus, as hereinafter more fully described.

A are air pumps or condensers, by which the air is forced into receivers or reservoirs, from which it is admitted to the engine in the ordinary manner. The upper ends of the piston-rods *B* of the air pumps or condensers *A* are pivoted to the outer ends of the arms *C*, rigidly attached to the rock-shaft *D*, which works in bearings in the upper ends of the posts *E*, or in some other suitable support. Any desired number of air-pumps *A* may be used, according to the capacity of the engine to be driven.

F are beams or bars attached to the ends of the rock-shaft *D*, and which are slotted horizontally from their ends to or nearly to the shaft *D*.

G and *H* are heavy weights, which fit into and slide back and forth in the slotted ends of the beams *F*, the weights *G*, upon one side of the shaft *D*, moving inward at the same time that the weights *H*, upon the other side of said shaft, move outward, thus rocking the shaft and working the pumps or condensers *A*.

I are connecting-rods, one end of which is pivoted to the weights *G*, and their other ends to the upper ends of the levers *J*, the middle parts of which are pivoted to the posts *K*, or to some other suitable stationary support.

To the lower ends of the levers *J* are pivoted the inner ends of the connecting-rods *L*,

the outer ends of which are pivoted to the lower ends of the bent or elbow levers *M*, which are pivoted at their angles to the posts *N*, or to some other suitable stationary support.

To the outer ends of the bent or elbow levers *M* are pivoted the lower ends of the connecting-rods *O*, the upper ends of which are pivoted to the ends of the working-beams *P*, which are pivoted to the upper ends of the slotted posts *K*, or to some other suitable stationary supports. The other ends of the working-beams *P* are connected to the weights *H* upon the other side of the rock-shaft *D* by a precisely similar arrangement of levers and connecting-rods—that is to say, by the connecting-rods *I*, levers *J*, connecting-rods *L*, bent or elbow levers *M*, and connecting-rods *O*—so that as the weights *G* are moved from the shaft *D* by the one system of levers and connecting-rods attached to the one end of the beam *P*, the other weights, *H*, may be moved toward the said rock-shaft *D* by the system of levers and connecting-rods connected with the other end of said working-beam *P*.

To the lower side of the central part of the working-beam *P* is attached, or upon it is formed, a toothed segment, *R*, the teeth of which mesh into the teeth of the segment *S*, formed upon or attached to the upper side of the central part of the working-beams *T*, pivoted in the slotted posts *K*, directly beneath the beams *P*, to which they are exactly similar.

U are connecting-rods, the upper ends of which are pivoted to the ends of the working-beams *T*, and the lower ends of which are pivoted to the crank-pins of the cranks *V*, which are attached to the ends of the shafts *W*.

X are weights, which are attached to the ends of the ropes *Y*, the other ends of which are attached to the drums *Z*, secured to the shafts *W* for the purpose of communicating motion to said shafts *W*, from which it is communicated to the working-beam *T*, and thence to the weights *G* and *H*, in the manner hereinbefore described.

If desired, motion may be communicated to the shafts *W* by springs or clock-work instead of by weights and drums, and this latter arrangement—viz., by springs or clock-work—I prefer, as being more compact and convenient.

I claim as new and desire to secure by Letters Patent—

1. The rock-shaft D, with which the piston-rods of the air pumps or condensers A are connected, operated by means of the sliding weights G and H, moving back and forth upon the slotted arms F, attached to said shaft D, substantially as herein shown and described, and for the purpose set forth.

2. The weights G and H, moved back and forth upon the slotted arms F from the working-beam P by means of the connecting-rods I, levers J, connection-rods L, bent or elbow levers M, and connecting-rods O, substantially as herein shown and described, and for the purpose set forth.

3. The combination of the toothed segment R, toothed segment S, working-beam T, connecting-rods U, crank V, and shaft W with each other and with the working-beam P to impart motion to said beam, substantially as shown and described.

The above specification of my invention signed by me this 12th day of October, 1867.

HALSEY MOORE.
